ARTHUR M. ALLEN, OF NEW YORK, N. Y.

Letters Patent No. 99,389, dated February 1, 1870.

IMPROVEMENT IN TOY PROPELLERS.

The Schedule referred to in these Letters Patent and making part of the same

To all whom it may concern:

Be it known that I, ARTHUR M. ALLEN, of the city, county, and State of New York, have invented a new and improved Toy Propeller; and I do hereby declare the following to be a full, clear, and exact description thereof, which will enable those skilled in the art to make and use the same, reference being had to the accompanying drawing, forming part of this specification, in which drawing—

Figure 1 represents a perspective view of this invention.

Figure 2 is a detached sectional view of the oblique joint between the front and hind wheels of the propeller, which forms the principal feature of this invention.

Similar letters indicate corresponding parts.

This invention relates to a toy propeller, which is provided with an oblique joint, in the connection between its front and hind wheels, in such a manner, that by turning the connection at its joint, the front wheel is thrown in an oblique position, and the propeller is caused to travel in a circle, toward the centre of which the front wheel is inclined, thereby avoiding any liability to upset.

In the drawing—

The letter A designates a toy propeller, which is made in the shape of a velocipede, or in the shape of any other device, supported by two wheels, B, behind, and by one wheel C, in front.

This propeller derives its motion from a spring, which connects with the axle of the hind wheels, by a train of gear-wheels, and the connection between the hind wheels and the front wheel is effected by a reach, D, which is composed of two sections, a b, the ends of which are joined together at an angle of forty-five degrees, (more or less,) and united by a screw-bolt, c, so as to form an oblique joint, best seen in fig. 2 of the drawing.

By turning the front section of the reach on the pivot c, the front wheel is thrown out of line with the hind wheels, and at the same time it is brought in an inclined position, so that the propeller will move on a circular track, toward the centre of which the front wheel is inclined.

If this oblique joint is applied to a toy velocipede, carrying a rider, the motion and position of this rider, in running on a circular track, are somewhat similar to those of a rider turning a curve on a full-sized velocipede.

What I claim as new, and desire to secure by Letters Patent, is—

The oblique joint, in the connection between the front and hind wheels of a toy propeller, substantially as set forth.

ARTHUR M. ALLEN.
